UNITED STATES PATENT OFFICE.

JOHN M. OLIN, HENRY H. WOOD, AND JOHN B. SMITH, OF EAST ALTON, ILLINOIS, AS-SIGNORS TO WESTERN CARTRIDGE COMPANY, OF EAST ALTON, ILLINOIS, A COR-PORATION OF DELAWARE.

METHOD OF AND APPARATUS FOR CAPPING DETONATORS.

Application filed December 30, 1922. Serial No. 609,953.

To all whom it may concern:

Be it known that we, JOHN M. OLIN, HENRY H. WOOD, and JOHN B. SMITH, all citizens of the United States, and residing 5 at East Alton, in the county of Madison, in the State of Illinois, have invented a certain new and useful Improvement in Methods of and Apparatus for Capping Detonators, of which the following is a specification.

10 This invention relates to methods of and machines for capping detonators, and more particularly those of the electrically ignited type.

One of the objects of this invention is to 15 provide a machine for capping a detonator by supplying thereto one or more sealing components in order to seal the connections in the shell.

Another object of this invention is to provide a machine, whereby during the capping operations the connections will be supported so as to avoid interference with the composition supplying mechanism and whereby the connections will be accurately positioned within the shell.

Another object of this invention is to provide a machine which will be simple in construction, effective in its action and economical.

30 Another object of this invention is to provide a process whereby the igniter terminals will not only be properly positioned but also sealed in the open end of the shell.

Further objects will appear from the detail description taken in connection with the accompanying drawing, in which:

Figure 1 is a plan of a machine embodying this invention;

Figure 2 is a section, somewhat enlarged, 40 on the line 2-2, Figure 1;

Figure 3 is a detail of the shell support and connection gage and table;

Figure 4 is a detail showing the spouts for supplying the composition; and

45 Figure 5 is an enlarged section of one of the sealed detonators.

Referring to the accompanying drawing and more particularly to Figure 5, the detonator as shown comprises a shell 1 which 50 may be of drawn metal, and has charge components 2 and 3 of any improved composition and arrangement; the upper end of this shell is beaded as shown at 4. In this shell are arranged the terminals 5 of the

connections 6 which pass through a plug 7 55 formed on the connections and of a suitable composition, a satisfactory one being a mixture of sulphur and graphite. The connections are insulated wires, which are stripped from where they project through the plug 60 and provided with a filament 8 of a suitable resistance wire. The plug 7 is formed on the connections extraneous of the shell and the plug terminal of the connection is inserted into the shell, as shown in Figure 5, 65 and secured by additional plugs 9 and 10 of sulphur and pitch respectively; these plug components are poured into the shell as hereinafter described so as to flow around the connections, and it will be noted that 70 the composition flows into the bead 4 so as to firmly secure and lock the parts together. The connections are coiled on the tube or other suitable support in order to provide a package 11 from which relatively short ends 75 of the connections project as shown in Figure 2.

Referring to Figures 1 to 4 inclusive, the machine as shown comprises a suitable base on which is mounted to rotate a carrier 15, 80 which has a rim 16 provided with a series of recesses or sockets 17 to receive the shells, the upper ends of each socket being enlarged as shown at 18 to receive the bead 4 so that the shoulder formed at the bottom of the 85 enlargement provides a recess for the bead 4. The rim 16 has formed or attached thereto a flange 19, over which the connections 6 are arranged to take in order to properly position the plug 7 on these connections in the shells, the coiled package 11 resting on the table 15.

Arranged above the table 15 and in spaced relation therearound are tanks 20 and 21, one of which is arranged to receive sulphur or a composition of sulphur and graphite, while the other receives pitch. These tanks may be heated in any suitable manner as by electrical heating coils (not shown). Each tank is provided with a series of spouts 22 (in this case three) which are arranged to discharge the components into a corresponding series of shells when alined therewith. Each tank has a series of measuring devices 23 corresponding to the spouts and arranged to measure quantities of the plug components into the shells, these measuring devices being mounted on a shaft 24,

2
 which is given a step by step rotative movement as hereinafter described in timed relation with the movement of the table, so that when a series of shells aline with the spouts 5 a predetermined, measured quantity of the plug component is fed into each shell; thereupon the table is given another step movement to aline another series of shells with the spouts and the measuring operation is 10 repeated. Each series of spouts has arranged therebelow a drip catcher 25 which is also operated in timed relation with the measuring device and the table.

Mounted on a suitable support 26, which 15 may form part of the base or the table, is a shaft 27 having a pulley 28 receiving power from any suitable source of power. Fixed to this shaft is a worm 29 meshing with a worm wheel 30 on a shaft 31. This 20 shaft has fixed thereto an element 32 of a Geneva movement, which meshes with a corresponding element 33 on the shaft 34, which has fixed thereto a bevel gear 35 meshing with a bevel segment 36 on the 25 table. The provision of this mechanism operates to impart a step by step movement to the table, with a period of rest between the movements, the movement in this instance being sufficient to successively cause 30 three shells to aline with the spouts.

The shaft 31 has fixed thereto a cam 37, the cam roll of which is mounted on an arm 38 connected with a pawl 39 cooperating with a ratchet 40. This ratchet is fixed to 35 a shaft which in turn has fixed thereto bevel gears 41 meshing with bevel gears 42 on shafts 43 having sliding couplings with the shafts 24. Accordingly the shafts 24 will be given a step by step movement so 40 as to operate the measuring devices 23 in timed relation with the movement of the table. The loose connections, however, enable the tanks to be shifted to properly 45 aline the spouts with the shells.

The shaft 31 has an additional cam 44 cooperating with a roll on the bell crank lever 45, which is connected by links 46 with the drip receivers 25, which are in the form of long arms and pivoted on the 50 base 26. Accordingly the drip receivers will be given movements from full to dotted positions, in order to move into and out of cooperative relation with the spouts, and this movement is in timed relation with the 55 movement of the table and of the measuring device.

Assuming that the table is given a movement in the direction of the arrow, Figure 1, the operation will be as follows: The 60 shells are placed on the table in front of the tank 20 and the plugs 7 are inserted in the shells with the connections 11-6 radiating inwardly therefrom and resting on the table, with these connections over the 65 gage or flange 19, so as to properly position

the plugs in the shells. After the table comes to rest with a set of shells in alignment with each set of spouts leading from the tanks 20 and 21, the drip receivers 25 are moved to dotted position so as to clear 70 the shells in alignment therewith. The measuring devices will now operate to measure into the shells predetermined or measured quantities of the plug components, the composition from the tank 20 forming the 75 plug 9 while the composition from the tank 21 forms the plug 10, the composition flowing not only into the shell but around the connections in order to thoroughly seal and secure the connections therein. It will be 80 understood, of course, that since the table is filled in front of the tank 20, there will be no filling from the tank 21 until the filled shells from the tank 20 reach the tank 21. Thereafter, however, the operation will 85 be continuous, and the shells and the connections sealed therein are taken from the table as it passes beyond the tank 21.

It will, therefore, be seen that the invention accomplishes its objects. The machine 90 is not only simple in construction but is economical and rapid in its operation. The separate components forming the plug are successively measured into the shell so as to flow therein and seal the connections 95 therein. Moreover the connections are not only supported clear of the measuring devices but in such a manner as to be convenient for manipulation and so as to properly position the terminals in the shell.

It is obvious that various changes may be made in details without departing from the spirit of this invention; it is, therefore, to be understood that this invention is not 100 to be limited to the specific details shown and described.

Having thus described the invention, what is claimed is:

1. In a machine for sealing detonators, the combination with a carrier having holders 110 for the shells, of means for supporting the connections adapted to position the terminals thereof within the shells, and means for supplying the sealing compound to said shells and over the connections therein.

2. In a machine for sealing detonators, the combination with a carrier having holders for the shells, of means for supporting the connections adapted to position the terminals thereof within the shells, and means 115 for successively supplying the components of a sealing plug to said shells and over the connections therein.

3. In a machine for sealing detonators, the combination with a carrier having holders for the shells, of means for supporting the connections adapted to position the terminals thereof within the shells, a sealing compound supply, a measuring device therefor adapted to direct the compound into the 120

125 compound into the shell, and a carrier 130 having a carrier having holders for the shells, of means for supporting the connections adapted to position the terminals thereof within the shells, a sealing compound supply, a measuring device therefor adapted to direct the compound into the

shells and over the connections therein, and means for operating said carrier and said devices in timed relation.

4. In a machine for sealing detonators, the combination with a carrier having holders for the shells, of means for supporting the connections adapted to position the terminals thereof within the shells, sealing compound tanks arranged along said carrier, a measuring device for each tank adapted to direct a component of a sealing plug to said shells and over the connections therein, and means for operating said carrier and said devices in timed relation.

15 5. In a machine for sealing detonators, the combination with a carrier having holders for the shells, of sealing compound supplying means adapted for cooperation with said carrier and the shells thereon, and means for supporting the connections clear of said supplying means, adapted to position the terminals within the shells, in order to cause the compound to form plugs within the shells and over said connections.

25 6. In a machine for sealing detonators, the combination with a carrier having holders for the shells, of sealing compound supplying means adapted for cooperation with said carrier and the shells thereon, said carrier being constructed and arranged to support said connections clear of said supplying means, adapted to position the terminals within the shells, in order to cause the compound to form plugs within the shells and over said connections.

35 7. In a machine for sealing detonators, the combination with a carrier having holders for the shells, of sealing compound supplying means adapted for cooperation with said carrier and the shells thereon, and a gage on said table for supporting said connections, adapted to position the terminals within the shells, in order to cause the compound to form plugs within the shells and over said connections.

45 8. In a machine for sealing detonators, the combination with a carrier having holders for the shells, of sealing compound sup-

plying means adapted for cooperation with said carrier and the shells thereon, said carrier having a table for supporting said connections, and means adapted to position the terminals within the shells, in order to cause the compound to form plugs within the shells and over said connections.

55 9. In a machine for sealing detonators, the combination with a carrier having holders for the shells, of sealing compound supplying means adapted for cooperation with said carrier and the shells thereon, said carrier having a table for supporting said connections, and a gage on said table adapted to position the terminals within the shells, in order to cause the compound to form plugs within the shells and over said connections.

60 10. In the art of making electrically ignited detonators, the process comprising, positioning the igniter terminals and their enveloping plug in the open end of the shell, and placing a sealing compound over the 70 plug and around the connections.

65 11. In the art of making electrically ignited detonators, the process comprising, positioning the igniter terminals and their enveloping plug in the open end of the shell, 75 and successively placing layers of sealing compound over the plug and around the connections.

70 12. In the art of making electrically ignited detonators, the process comprising, 80 placing the igniter terminals and their enveloping plug in the open end of the shell, and positioning the terminals and plug by the connections.

75 13. In the art of making electrically ignited detonators, the process comprising, 85 placing the igniter terminals and their enveloping plug in the open end of the shell, positioning the terminals and plug by the connections, and placing a sealing compound 90 over the plug and around the connections.

In testimony whereof we affix our signatures this 28th day of November, 1922.

JOHN M. OLIN.

HENRY H. WOOD.

JOHN B. SMITH.
